UNITED STATES PATENT OFFICE.

GEORGE W. PRICE, OF CHICAGO, ILLINOIS.

HAT-FRAME FORMER.

No. 823,696.

Specification of Letters Patent.

Patented June 19, 1906.

Application filed October 3, 1905. Serial No. 281,139.

To all whom it may concern:

Be it known that I, GEORGE W. PRICE, a citizen of the United States, residing at Chicago, in the county of Cook and State of Illinois, have invented new and useful Improvements in Hat-Frame Formers, of which the following is a specification.

This invention relates to a device upon which wire frames for women's hats are formed; and it consists principally of a base having a post upon which is mounted two heads one of which has projecting arms carrying rods each having at its upper end a hook in which the wire is held when forming a hat-frame. These rods are adjustably attached to the arms, so as to fix them in various positions, and thus secure different forms for hats. The wires are arranged on the rods by hand, and when a hat-frame has been formed the hooks on the rods can be disengaged simultaneously by releasing a lever operating a toggle device. The hat-frame is then simply lifted off by the operator.

In the accompanying drawings, Figure 1 is a side elevation of the machine, only two sets of rod-holders being shown, whereas eight sets are practically employed. Fig. 2 is a plan of one of the heads. Fig. 3 is a vertical section of same. Fig. 4 is a detail of the head, showing the manner of attaching one of the arms. Fig. 5 is a detail in section of means of attaching the rods. Figs. 6 and 7 are details of the arms. Fig. 8 is a plan view showing a hat-frame on the device. Fig. 9 is a detail illustrating the action of the arms.

In the drawings, 6 indicates a base upon which is mounted a central post 8.

10 is an upper head having radial vertical slots 14^a and a horizontal circular groove 14. 40 This head has a central bore 14^b and is provided with a sleeve 14^c and is rotatable on the post, but is held in fixed vertical position on the post 8 by pins 10^d. Below the upper head is a head 10^e, slideable up and down on the post 8, and 10^e is a cross-pin in the post to limit the downward movement of the head. Coiled on the post in compression between the said heads is a spring 11. Attached to the head 10 are radial arms 7, each of which 50 is pivotally connected at its outer end to a lower angular arm 7^a, pivoted to the lower head 10^e. Supported upon these arms 7^a are a series of vertical rods 9, each of which is adjustably attached thereto, preferably by means of a bolt 16, having a slot 16^a and a tightening-nut 16^b. The tops of the rods 9

are provided with hooks or notches 9^a. Each arm 7 has at its inner end a cross-pin 7^b, which is inserted in the groove 14 and slot 14^a, and small vertical pins 7^c secure the same in place. The arms 7^a are secured similarly in the lower head 10^e, which is substantially the same in structure as the head 10. The heads 10 and 10^e are connected by links 20 and 20^a to a lever 20^b, by the movement of which the lower head is raised or allowed to drop under the pressure of the spring. When the toggle-lever is thrown or lifted to full extent beyond center, it will lock the lower head in raised position while the hat-frame is being made, as indicated in dotted lines in Fig. 9.

It being understood that the rods 9 are inclined or adjusted to suit the style of hat being made, the head 10^e is lifted by the lever 75 and locked in its upper position. This spreads the rods. The circular or round-and-round wires 26 are first placed by being wound around the tops of the selected rods 9 and engaged in the notches. The radial 80 wires 21 are then applied to complete the frame. Then the lever 20^b is snapped or turned back and the head 10^e drops. The effect of this is to draw the rods 9 down and in, as shown in full lines in Fig. 9, thereby releasing the wires from the notches and allowing the hat-frame to be removed.

The form of the hat may be round, oval, or any other shape, inasmuch as the rods 9 are capable of being raised, lowered, tilted, and 90 arranged to suit any desired shape. Naturally the inner rods will support the crown or head wires of the frame and the outer rods the brim; but, as stated, the rods are capable of adjustment according to the shape desired, the various wires being supported by the rods most conveniently located for the purpose.

What I claim as new, and desire to secure by Letters Patent, is—

1. A former for wire hat-frames, comprising a central post, upper and lower heads rotatable thereon and having a spring in compression therebetween, radial arms pivoted at their inner ends to one of the heads and having supporting connections to the other head, and upright rods connected to the arms and having means to engage wires, and adapted to tilt when the heads are pushed toward each other.

2. In a former for wire hat-frames, the combination of a central post, heads mount-

ed thereon radial arms pivotally connected to one of the heads and having supports connected to the other, upright rods supported on said arms, a spring in compression between the heads, and a lever connected to the respective heads and arranged to draw the same together.

3. In a former for wire hat-frames, the combination of a central post, upper and lower heads mounted thereon, sets of radial arms pivotally connected at their inner ends to the respective heads and to each other at their outer ends, upright rods supported on one of said sets, and a lock-lever connected to the respective heads and adapted to draw the same together.

4. In a hat-frame former, in combination, an upright post having upper and lower heads thereon movable to and from each other, and upper and lower sets of arms which are hinged at their inner ends to the heads respectively, and at their outer ends to each other, wire-engaging rods carried by the lower set of arms, and means to move the heads toward or from each other.

In testimony whereof I have signed my name to this specification in the presence of two subscribing witnesses.

GEORGE W. PRICE.
